Charles M. Culp

BY *Alphonse Bois*
his ATTORNEY.

UNITED STATES PATENT OFFICE.

CHARLES M. CULP, OF SOUTH BEND, INDIANA.

RAILWAY-RAIL BED.

SPECIFICATION forming part of Letters Patent No. 431,253, dated July 1, 1890.

Application filed November 30, 1889. Serial No. 332,077. (No model.)

To all whom it may concern:

Be it known that I, CHARLES M. CULP, a citizen of the United States, residing at South Bend, in the county of St. Joseph and State 5 of Indiana, have invented certain new and useful Improvements in Railway-Rail Beds; and I do hereby declare the following to be a full, clear, and exact description of the invention, such as will enable others skilled in the 10 art to which it appertains to make and use the same.

My invention relates to the construction of railway-rail beds; and my object is to produce a structure which will effectually prevent 15 creeping or spreading of the rails and at the same time admit of free expansion and contraction thereof.

With this end in view my invention consists in the peculiar features and combinations of parts more fully described hereinafter, 20 and pointed out in the claims.

Referring to the accompanying drawings, Figure 1 is a plan view of my complete structure, and Fig. 2 a side elevation.

25 The reference-letter A indicates the main or anchor sleeper, which is made much heavier and larger than the ordinary ties, and is situated intermediate of the opposite ends of the rail. The preferred position of the anchor 30 sleeper or tie is midway between the ends of the rails. At this point each rail B is provided with notches or suitable apertures b on each side, and through these notches spikes b' are driven into the sleeper A. The rail is thus securely 35 anchored at its central portion, and any movement of the same in a longitudinal or lateral direction is prevented. The ties C are placed on either side of the sleeper A in the usual manner, and the rails are spiked thereto in 40 the ordinary way. On the outside of the track the metallic stringers D are situated. These stringers are securely fastened to the

anchor-sleeper A at their center by means of spikes or bolts d; and are secured in like manner to one or more ties on either side of the 45 main sleeper. It will thus be apparent that while the rails are securely anchored at the middle and prevented from spreading or creeping at the same time free expansion and contraction is allowed between the center and 50 the joints.

The stringers serve to keep the anchor-tie firmly in position and to generally strengthen and brace the whole structure. These stringers are preferably made of metal; but it is 55 evident that they may be made of any other suitable material, and it is also evident that many other slight changes which might suggest themselves to a skilled mechanic could be resorted to without departing from the 60 spirit and scope of my invention. Hence I do not limit myself to the precise construction herein shown.

Having thus described my invention, what I claim as new, and desire to secure by Letters 65 Patent, is—

1. The combination of an anchor-sleeper, the rails secured thereto from lengthwise movement, ties on either side of said sleeper, and a stringer secured to said sleeper and said 70 ties, as and for the purpose set forth.

2. The combination of an anchor-sleeper at the middle of a rail-section, the rails provided with notches at this point on both sides, fastening devices engaging these notches and 75 said sleeper, ties on either side of the anchor-sleeper, and stringers secured to said sleeper and said ties, substantially as described.

In testimony whereof I affix my signature in presence of two witnesses.

CHARLES M. CULP.
